UNITED STATES PATENT OFFICE.

BERTRAM GEORGE AIKEN HARKNESS AND HEINRICH FRANZ VOSSELER, OF STRATFORD, TARANAKI, NEW ZEALAND.

OSCILLATING VACUUM PUMP.

1,427,533.

Specification of Letters Patent. Patented Aug. 29, 1922.

Application filed March 29, 1920. Serial No. 369,713.

To all whom it may concern:

Be it known that we, BERTRAM GEORGE AIKEN HARKNESS and HEINRICH FRANZ VOSSELER, both citizens of the Dominion of New Zealand, and residing at Stratford, in the Provincial District of Taranaki, New Zealand, subjects of the King of Great Britain and Ireland, have invented new and useful Improvements in an Improved Oscillating Vacuum Pump, of which the following is a specification.

This invention relates to vacuum pumps and provides an improved construction thereof, which is also capable of being converted into a vacuum engine, when required.

According to the invention the pump has a cylinder adapted to oscillate on trunnions, and a slide valve with hinged flaps at the ends, working on a valve face on the cylinder.

The cylinder is caused to oscillate below the valve by the operation of the piston rod, said valve being held against reciprocating motion by a rod pivoted to a fixture.

The interior of the slide valve is connected with a vacuum pipe line, either through a central port opening through the valve face and a passage through the cylinder wall and a hollow trunnion or by means of a flexible connection.

A rear and a front port opening into the back end and the front end of the cylinder respectively also open through the valve face one at each side of the central port and are alternately connected with or opened to the central port, or the interior of the valve, by the oscillation of the cylinder.

In order to cause a vacuum to be produced the crank shaft, is rotated in the opposite direction, to which a pump crank shaft is usually rotated.

As the pump piston travels its first stroke the cylinder becomes filled with rarefied air, which has to be compressed to atmospheric pressure before it can be driven out.

The hinged flaps prevent the entrance of air to the cylinder through the rear and front ports, on the exhaust side of the piston, thereby preventing the creation of back pressure in the pump and making same easier to drive.

At the same time the hinging of the flaps permits the latter to lift and allow the

exhaust pressure to escape on the necessary degree of compression being obtained.

By removing the hinged flaps from the slide valve and causing vacuum to act in the valve through the central port, passage, and hollow trunnion, or through the flexible connection, the crank shaft of the machine will rotate in the ordinary way and develop power as an ordinary engine.

The invention will be further described in conjunction with the accompanying drawing in which:

Figure 1 is an elevation and.

Figure 2 a plan view of the pump, and

Figure 3 a sectional elevation of same.

Figure 4 is a cross section of the cylinder and the valve while

Figures 5 and 6 are an enlarged longitudinal section and a cross section respectively of the valve and portion of the cylinder, in a modified form.

The pump cylinder 1 has trunnions 2 and 3 of which trunnion 2 is hollow and communicates by means of the passage 4 in the cylinder wall with the central port 5 opening through the valve face 6.

The trunnions 2 and 3 rest in bearings 19, and the hollow trunnion 2 is adapted to be put into communication with a vacuum pipe line connected up to where desired.

The rear port 7 and the front port 8 in the valve face 6, open into the rear and front ends respectively of the cylinder 1.

A rear cover 9 and a front cover 10 are fitted to the cylinder 1 within which is a piston 11 operated by the piston rod 12 passing through a stuffing box 13, and connected to a crank shaft carrying a fly wheel 20, said crank shaft being mounted in bearings on the base plate 21 in the usual way.

The bearings 19 for trunnions 2, 3 are provided on pedestals 14 integral with the base plate 21.

The hollow slide valve 15 is pivoted to one end of the rod 16, the other end of which is pivoted to a fixed column or standard 22 preferably also on the base plate 21.

The interior 17 of the valve 15 is always open to the port 5, the latter being adapted to be connected by said valve 15, alternately with the rear port 7 and the front port 8.

Hinged flaps 18 are provided one at each end of the valve 15.

The machine when used as a vacuum pump is driven by an internal combustion engine, or other suitable means, so that its crank shaft is rotated in a counter clockwise direction, Figure 3.

The rotation of the crank shaft and the movement of the piston rod 12, cause the cylinder 1 to oscillate in the bearings 19 beneath the valve 15, which is held against 10 backwards and forward movement by the rod 16, the flaps 18 preventing the entrance of air to the cylinder 1 through the ports 7, 8 but allowing exhaust pressure to escape through the latter.

15 In Figures 5 and 6 the central port 5 is dispensed with, and the connection from the pipe line is made direct to the valve 15 by means of a flexible connection 23.

By removing the flaps 18, and connecting the machine up with a vacuum creating source through either the hollow trunnion 2, passage 4 and port 5, or the flexible connection 23, so that vacuum is caused to act continuously in the interior 17 of the valve 15, the crank shaft is caused to rotate in the usual direction and develop power as a vacuum driven engine.

What we do claim and desire to secure by Letters Patent of the United States is:—

30 1. In a pump, an oscillating cylinder provided with a valve seat, a piston reciprocally mounted in the cylinder, said cylinder having ports extending from the valve face to the opposite extremities of the cylinder, a hollow valve movable on said valve face, and a link pivotally connected at one end at a point removed from the axis of movement of the cylinder and connected at its opposite end with the valve whereby the latter is moved across the valve seat co-incident with the oscillation of the cylinder.

45 2. In a pump, an oscillating cylinder provided with a valve face and ports extending from the valve face to the opposite extremities of the cylinder, a piston reciprocally mounted in the cylinder, a valve movable over said valve face to alternately uncover said ports, means for limiting the movement of the valve with respect to the 50 cylinder whereby, during oscillation of the

latter, the ports are alternately uncovered, and pivoted flaps carried by the valve arranged to cover the ports and adapted to be opened by the internal fluid pressure in the extremities of the cylinder.

55

3. In a pump, an oscillating cylinder provided with a valve face having ports extending from the valve face to the opposite extremities of the cylinder, a piston reciprocally mounted in the cylinder, a valve movable on said valve face to alternately uncover said ports, a connecting link pivotally connected with the valve at one end, and a relatively stationary member pivotally connected with the opposite end of the link 60 at a point removed from the axis of oscillatory movement of the cylinder whereby the ports are alternately uncovered co-incident with oscillation of the cylinders.

65

4. In a pump, an oscillating cylinder provided with a valve face and ports extending from the valve face to the opposite extremities of the cylinder, a piston reciprocally mounted in the cylinder, a valve movable over the valve face to alternately uncover the ports, a relatively stationary standard, and a link pivotally connected at one end with the standard at a point removed from the axis of oscillation of the cylinder and connected at its opposite extremity with the valve whereby reciprocating movement is imparted to the latter across the valve face co-incident with oscillatory movement of the cylinder.

70

5. In a pump, a cylinder provided with a valve face having ports therein, a valve movable across the valve face to alternately uncover the ports, and flaps pivotally connected with the extremities of the valve movable across the valve face and constituting pressure relieving valves actuated by internal pressure in the cylinder.

75

In testimony whereof we have signed our names to this specification in the presence of two witnesses.

BERTRAM GEORGE AIKEN HARKNESS.
HEINRICH FRANZ VOSSELER.
